STOCK HANDLING GRAB

Jack Breslav, New Haven, Conn.

Application March 22, 1944, Serial No. 527,592

9 Claims. (Cl. 294—67)

This invention relates to improvements in stock handling grabs and more particularly to a grab of the hook type for handling tubes or bars as they are transferred from one station to another in a manufacturing plant.

The grab of this invention is particularly useful in lifting a load of piled-up tubes, or bars, from a table, or other load supporting means, by being adapted to be swung under the load so supported and then manipulated to embrace the load to prevent piled-up tubes, or bars, from shifting as they, as a load, are raised from the previous supporting means. In order to so raise a plurality of piled-up tubes, or bars, without undue shifting of the same, which might damage their finish or distort them, it is contemplated as an object of this invention to provide in the grab structure a side supporting member which is arranged to be swung, or rotated, to adapt it to be turned flatwise to permit it to be slid under the load and then turned upwardly into a load bracing position.

Another object of this invention is to provide a grab having a series of stationary members, or arms for bracing one side of a pile of tubes, or rods, and a series of members, or arms, which are adapted to be turned in unison to permit them to be swung transversely under the load and then be turned upwardly to brace the other side of the pile of tubes, or rods.

A further object of this invention is to provide an improved stock handling grab which will be relatively inexpensive to manufacture, simple in construction, compact, and very efficient and durable in use.

With the above and other objects in view, which will appear as the description proceeds, there has been illustrated in the accompanying drawings a form in which the invention may be conveniently embodied in practice.

In the drawings:

Figure 1 is a broken top plan view of a stock handling grab embodying the features and principles of this invention;

Figure 2 is a broken front view of the grab shown in Figure 1;

Figure 3 is an end view of the grab;

Figure 4 is an enlarged broken view looking in the direction of arrow 4 in Figure 2;

Figure 5 is an enlarged sectional view taken on the line 5—5 of Figure 2;

Figure 6 is an enlarged broken view looking in the direction of arrow 6 of Figure 3; and

Figure 7 is a view showing an arrangement

wherein an electric motor is adapted to actuate certain operable parts of the grab.

Referring now to the drawings wherein like reference numerals designate like parts throughout the several views the numerals 11 and 12, see Figures 2 and 3, denote, in dotted lines, spaced apart legs of a tube, or rod, supporting table, or the like, having laterally extending and vertically spaced apart cross-bars 13 and 14, and upwardly and outwardly extending arms 15 and 16 adapted to support and hold a pile of a plurality of tubes, or bars, 17. The legs 11 and 12 are tied together by lengthwise extending front and rear beams 18 and 19 respectively which are spaced from and below the cross-bars 13 to form a space therebetween. It is obvious that the cross-bars 13 form the top of the table, or supporting means, for the tubes, or bars, 17, and that the angularly disposed arms 15 and 16 form the embracing means to maintain the pile of tubes, or bars, 17 in a determined desired shape.

The stock handling grab, in accordance with the features and principles of this invention, is adapted to be slipped under the pile of tubes, or bars, 17 and, without disturbing the shape of the same, to raise the same from the table, or supporting means, and transport it to another location. The grab illustrated includes a carrying member having crane hook engaging loops 21 secured thereto whereby the grab may be lifted and moved from one position to another, and being composed of adjacent channel beams 22 and 23 between which the loops 21 are disposed. In this instance a counterbalancing beam 24 is provided spaced from the carrying beams 22, 23 and secured thereto by cross-bars 25 and 26.

Depending from the carrying beams 22, 23 are a plurality of tube, or bar, engaging carrier arms 27 herein shown as each being composed of a short member 28, an angular outwardly disposed member 29, a vertical member 31, and a horizontal member 32, the last member 32 forming the base of the arms 27 and upon which the tubes, or bars, 17 will be supported after being engaged thereby during the operation of a grab. A supplemental tube, or bar, engaging member 33 is provided and suitably secured, as by welding, to the base member 32. The member 33 extends upwardly from the base member 32 substantially at the same angle as the table arm 15.

A rod 34 extends along and is rotatably supported from each base member 32 in suitable bearings 35 and 36 secured to said base member. The inner end 37 of said rod 34 is bent 55 away from the remainder at an angle substan-

tially the same as the angle of the table arm 16. The rod end 37 and the member 33 with the base member 32 form a support, or cradle, to embrace the pile of tubes, or bars, 17 of determined desired shape. An operating bar 38 has its lower end secured to the outer end of at least one of the rods 34 and extends substantially at right angles therefrom. The bar 38 is provided with a handle 39 at its upper end by which it may be swung to rotate the rod 34 in its bearings 35 and 36. The handle 39 is pivoted to the bar 38 to be rotated to cause a latch member 41 to be swung over the end of a latch catch 42, secured to the adjacent vertical member 31 of the carrier 27, to prevent the bar 38 from inadvertently swinging out of its vertical position. When the bar 38 is in its vertical position, as shown, the rod end portion 37 extends upwardly in tube, or bar, 17 embracing position.

As shown in Figure 1 a plurality of carriers 27 are provided and each of the rods 34 of the end carriers is provided with an operating bar 38 and handle 39. The rod 34 of each of the intermediate carriers 27 have a short bar 43 (see Figure 2) secured to the inner end thereof, of which bar 43 extends substantially at right angles to the associated rod 34. The upper end of each bar 43 and the bars 38 are connected by a rod 44 so that they will swing in unison, the rod 44 being pivotally connected to each bar by a bolt 45.

In order to limit the amount the grab of this invention is lowered and to insure that it is lowered the same amount each time it is used with tables, or other supports, of the same height from the floor, provision is made to stop the grab in its downward movement by means of a vertically adjustable stop bar 46. The bar 46 is slidably secured to one of the carriers 27 by being guided at its upper end in a clip 47 secured to the vertical member 31, and a clamp screw 48 extending through a slot 49 provided in the bar 46 and screw-threaded into the member 31.

The arrangement shown in Figure 7 whereby the connecting rod 44 may be actuated by an electric motor 51 includes a motor supporting bracket 52 having a gear pinion 53 on its shaft the teeth of which meshes with the teeth of a gear quadrant 54 pivoted to a bracket 55. The brackets 52 and 55 are herein shown secured to and extending from one of the end arms 27 of the load carrying grab. The rod 44 is pivoted at 56 to the quadrant 54 in such a manner that rocking movement of the quadrant 54 by the motor 51 will impart the required movement to the rod 44 to swing the bars 38 and 43 and through them to swing the rod ends 37 into the desired horizontal position for the purpose above described.

In operation the grab of this invention is lowered with the rod end portions 37 disposed in a horizontal position as indicated in dotted lines in Figures 1 and 2. When the rod portions 37 are in a horizontal position, the bars 38 and 43 are in a horizontal position and the bars 38 rest upon stop lugs 57 extending out from the vertical members 31. The grab is lowered until the lower end of stop bar 46 strikes the floor and is then moved horizontally to dispose the base members 34 in under the load of tubes, or rods, supported on the table, or like support.

When the grab is in position under the load, see Figure 3, the operating bar 38 is swung up-

wardly to dispose the rod portions 37 in back of the load. The swinging movement of the bars 38 and 43 is limited by stops 58 which extend out from and are secured to the adjacent vertical members 31 and which are herein shown as supports for the latch catches 42. The latch member 41 is now swung into latched position with the latch catch 42, see Figure 5, and the grab is operated by its supporting crane to engage and lift the load from its support.

By providing in a grab a plurality of rod end portions 37 which are swingable from a horizontal position extending lengthwise of the tubes, or rods, of the pile, permits the use of such a grab to engage and lift loads from the top of a table, or other support, herein beams 13, which is spaced closely from the floor, or wherein the table top is spaced closely from reinforcing beams such as 14, 18, and 19, which in turn are supported from the floor by legs 11 and 12. The adjustable stop bar 46, when once adjusted to the table, or other support, supporting the load, locates the proper position of the grab whereby it may be swung under the load without interference, is clamped in place and assists the operator of the crane in the operation of the grab.

While there has been disclosed herein one form in which the invention may be embodied in practice it will be understood that the novel features and principles of this invention may be embodied in other specific forms without departing from the spirit and essential attributes thereof, and it is therefore desired that the present embodiment be considered in all respects as illustrative and not restrictive, reference being had to the claims rather than to the foregoing description to indicate the scope of the invention.

Having thus fully disclosed the invention, what is claimed as new and for which it is desired to secure Letters Patent is:

1. In a load handling grab having a load supporting base and an upstanding first arm, and a second arm spaced laterally from the first arm and being swingable from an upstanding position to a substantially horizontal position whereby the base and the second arm may be moved laterally in under, and closely adjacent to the bottom, of a load spaced upwardly from a support.
2. In a load handling grab having a load supporting base and an upstanding first arm, and a second arm spaced laterally from the first arm and being swingable from an upstanding position to a substantially horizontal position, whereby the base and the second arm may be moved laterally in under, and closely adjacent to the bottom, of a load spaced upwardly from a support, an operating bar adjacent to the first arm, and means pivotally supported on the base and connecting said second arm to said operating bar.
3. In a load handling grab having a load supporting base and an upstanding first arm, and a second arm spaced laterally from the first arm and being swingable from an upstanding position to a substantially horizontal position whereby the base and the second arm may be moved laterally in under, and closely adjacent to the bottom, of a load spaced upwardly from a support, and an adjustable vertically movable bar secured to said first arm to limit the amount the grab is lowered.
4. In a load handling grab having a load supporting base and an upstanding first arm, and a second arm spaced laterally from the first arm

and being swingable from an upstanding position to a substantially horizontal position whereby the base and the second arm may be moved laterally in under, and closely adjacent to the bottom, of a load spaced upwardly from a support, an operating bar adjacent to the first arm, means pivotally supported on the base and connecting said second arm to said operating bar, and a latch device including a latch member pivoted to said operating bar and secured to a handle to engage a latch catch secured to said first arm.

5. In a load handling grab, a carrying member, a plurality of load supporting base bars spaced apart along the length of said member, a first arm secured to and extending upwardly from an end of each supporting base bar to form a side brace for the load, a second arm disposed at the other end of each supporting base bar and being swingable from an upstanding position to a substantially horizontal position whereby the base bars and the second arms may be moved laterally in under, and closely adjacent to the bottom of a load spaced upwardly from a support, and means to tie all of said second arms together to swing in unison.

6. In a load handling grab, a carrying member, a plurality of load supporting base bars spaced apart along the length of said member, a first arm secured to and extending upwardly from an end of each supporting base bar to form a side brace for the load, a second arm disposed at the other end of each supporting base bar and being swingable from an upstanding position to a substantially horizontal position whereby the base bars and the second arms may be moved laterally in under, and closely adjacent to the bottom, of a load spaced upwardly from a support, means to tie all of said second arms together to swing in unison, and an operating bar adjacent to one of the first arms, means pivotally supported on a base bar and connecting the operating bar and the associated second arm.

7. In a load handing grab, a carrying member, a supporting base bar spaced downwardly from said member, an upstanding arm secured to an

end of said base bar and connecting it to said member, a second arm at the other end of said base bar, an operating bar adjacent the upstanding arm, means extending along said base bar, 5 connecting the operating bar with said second arm and being pivotally mounted on said base bar, and a stop member on said upstanding arm to limit the downward swinging movement of said operating bar and said second arm into a substantially horizontal position.

10 8. In a load handling grab, a carrying member, a plurality of load supporting base bars spaced apart along the length of said member, a first arm secured to and extending upwardly from an end of each supporting base bar to form a side brace for the load, a second arm disposed at the other end of each supporting base bar and being swingable from an upstanding position to a substantially horizontal position 15 whereby the base bars and the second arms may be moved laterally in under, and closely adjacent to the bottom, of a load spaced upwardly from a support, means to tie all of said second arms together to swing in unison, an operating bar adjacent to one of the first arms, and means pivotally supported on a base bar connecting the operating bar and the associated second arm, and a vertically movable bar adjustably secured to one of said first arms to limit 20 the lowering movement of the grab.

25 9. In a load handling grab, a carrying member, a plurality of supporting base bars spaced along the length of said member, an upstanding arm secured to an end of each base bar, a swingable arm at the other end of each base bar, an operating bar adjacent to each of the upstanding arms, a tie rod connecting said operating bars, said operating bars being connected to said swingable arms, stop means to limit the upward 30 swinging movement of said swingable arms, and stop means to limit the downward swinging movement of said swingable arms into a substantially horizontal position substantially parallel to said supporting member.
